(57) **CLAIM**

The ornamental design for a nestable beverage crate, as shown.

DESCRIPTION

FIG. 1 is a perspective view of a nestable beverage crate, showing our new design.

FIG. 2 is a first side view of the nestable beverage crate of FIG. 1.

FIG. 3 is a second side view of the nestable beverage crate of FIG. 1.

FIG. 4 is a first end view of the nestable beverage crate of FIG. 1.

FIG. 5 is a second end view of the nestable beverage crate of FIG. 1.

FIG. 6 is a top view of the nestable beverage crate of FIG. 1; and,

FIG. 7 is a bottom view of the nestable beverage crate of FIG. 1.

The broken lines showing portions of the crate are for the purposes of illustrating environment and form no part of the claimed design.
